ALTAR CARD STAND

Daniel Francis Houlihan, Washington, N. J.
Application August 31, 1954, Serial No. 32,093

Term of patent 7 years

(Cl. D29—23)

To all whom it may concern:

Be it known that I, Daniel Francis Houlihan, a citizen of the United States of America and residing at Washington, county of Warren, and State of New Jersey, have invented a new, original, and ornamental Design for an Altar Card Stand, of which the following is a specification, reference being had to the accompanying drawings, forming a part thereof.

I claim:

The ornamental design for an altar card stand, as shown.
